(57) **CLAIM**

The ornamental design for a golf glove, as shown and described.

DESCRIPTION

FIG. 1 is a top perspective view of the palm of the golf glove of this invention;

FIG. 2 is an elevation view of the finger-tip end of the golf glove of this invention;

FIG. 3 is a plan view of the palm of the golf glove of this invention;

FIG. 4 is an elevation view of the wrist end of the golf glove of this invention;

FIG. 5 is a thumb-side elevation view of the golf glove of this invention; and,

FIG. 6 is a little-finger-side elevation view of the golf glove of this invention.

The dot-dash broken lines represent the bounds of the claim. The dash-dash broken lines illustrate portions of the golf glove and form no part of the claimed design. The heavier dash-dash broken lines in the wrist portion of the glove represent stitching and form part of the claimed design.

1 Claim, 3 Drawing Sheets
